Genus and species: *Pelargonium peltatum*.
Variety denomination: 'KLEPP17459'.

**CROSS REFERENCE TO RELATED
APPLICATION**

The present application claims priority to Switzerland Plant Variety Protection Application No. 17-3147, as filed on May 24, 2017, the entire contents are herein incorporated by reference for all the application teaches and discloses. A European Community Plant Variety Protection Application was filed on May 30, 2017, Application No. 2017/1438.

BACKGROUND OF THE NEW PLANT

The present invention comprises a new and distinct variety of *pelargonium*, botanically known as *Pelargonium peltatum* and hereinafter referred to by the variety name 'KLEPP17459'. 'KLEPP17459' originated from a hand pollination in July 2012 in Stuttgart, Germany between the female proprietary *pelargonium* variety PP-2008-0129 (unpatented) and the male *pelargonium* variety ATLANTIC 'Royal White' (unpatented).

Seeds from the hand pollination were obtained and sown and plants were grown for evaluation. A single plant was selected in June 2013 and subsequently named 'KLEPP17459'. In September 2013 'KLEPP17459' was first vegetatively propagated in Stuttgart, Germany by vegetative cuttings from branches. 'KLEPP17459' was found to reproduce true to type in successive generations of asexual propagation via vegetative cuttings in Stuttgart, Germany.

SUMMARY

The following are the most outstanding and distinguishing characteristics of this new variety when grown under normal horticultural practices in Stuttgart, Germany.

2

1. White flowers;
2. Early flowering; and
3. A hanging habit.

DESCRIPTION OF THE PHOTOGRAPH

10 This new *pelargonium* plant is illustrated by the accompanying photograph which shows an overall view of the plant. The photograph is of an approximately 10 week old plant old plant grown in Stuttgart, Germany outdoors in July 2015. The colors shown are as true as can be reasonably obtained by conventional photographic procedures.

DESCRIPTION OF THE NEW VARIETY

15 The following detailed descriptions set forth the distinctive characteristics of 'KLEPP17459'. The data which define these characteristics were collected from asexual reproductions carried out in Stuttgart, Germany. Data was collected on plants grown three months after planting in 20 Stuttgart, Germany under a glass covered greenhouse in April 2018. Color references are to The R.H.S. Colour Chart of The Royal Horticultural Society of London (R.H.S.), 5th edition (2007).
